US0D1100899S

(12) **United States Design Patent** (10) Patent No.: **US D1,100,899 S**
(45) Date of Patent: ** Nov. 4, 2025

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/849,378**

(22) Filed: **Aug. 10, 2022**

Related U.S. Application Data

(63) Continuation of application No. 29/664,211, filed on Sep. 24, 2018, now Pat. No. Des. 960,885, which is a continuation of application No. 29/612,240, filed on Jul. 31, 2017, now Pat. No. Des. 832,249, which is a continuation of application No. 29/560,682, filed on Apr. 8, 2016, now Pat. No. Des. 797,096, which is a continuation of application No. 29/533,841, filed on Jul. 22, 2015, now Pat. No. Des. 772,861.

CLAIM

The ornamental design for an electronic device as shown and described.

DESCRIPTION

FIG. 1 is a top front perspective view of an electronic device showing our new design;

FIG. 2 is a top rear perspective view thereof;

FIG. 3 is a bottom rear perspective view thereof;

FIG. 4 is bottom front perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines illustrate structure or features which form no part of the claimed design.
